(57) **CLAIM**

The ornamental design for a nail curing machine, as shown and described.

DESCRIPTION

FIG. 1 is a perspective view of a nail curing machine showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is an exploded perspective view of the nail curing machine;

FIG. 9 is an exploded bottom perspective view thereof;

FIG. 10 is an exploded front elevational view thereof;

FIG. 11 is an exploded rear elevational view thereof;

FIG. 12 is an exploded right-side elevational view thereof;

FIG. 13 is an exploded left-side elevational view thereof;

FIG. 14 is an exploded top plan view thereof; and,

FIG. 15 is an exploded bottom plan view thereof.

The broken line showing of a universal serial bus (USB) port is included for the purpose of showing environmental structure and forms no part of the claimed design.
